UNITED STATES PATENT OFFICE.

AMAND U. LORINET AND ZACHARIE P. AUBERTELLE, OF CHALONS-SUR-MARNE, FRANCE.

SEWING-MACHINE TAKE-UP.

• SPECIFICATION forming part of Letters Patent No. 244,268, dated July 12, 1881.

Application filed March 15, 1881. (No model.)

To all whom it may concern:

Be it known that we, AMAND ULYSSE LORINET and ZACHARIE PRUDENT AUBERTELLE, of Chalons-sur-Marne, in the Department of 5 Marne, in the Republic of France, have invented certain new and useful Improvements in Sewing-Machines; and we do hereby declare the following to be a full, clear, and exact description of the invention, such as will enable 10 others skilled in the art to which it appertains to make and use the same, reference being had to the accompanying drawing, and to letters of reference marked thereon, which form a part of this specification.

15 Our invention has relation to devices for preventing "slip-stitches" in operating sewing-machines; and it consists in the construction and arrangement of parts of a device which can be attached to any sewing-machine, and is operated by the vertically-reciprocating needle-bar, as hereinafter more fully set forth.

In the annexed drawing I have shown a portion of the frame and needle-bar of a sewing-machine with the attachment and also the 25 thread in side elevation.

The letter A designates the front part or box of the so-called "goose-neck" or frame of the machine, which forms the bearings for the presser-foot (not shown) and needle-bar F. 30 Upon this box or frame is pivoted, at B, a lever, C, which projects out toward and on one side of the needle-bar, which it touches on one side, and is bent at its outer end, as shown at C'. This lever C C' is made with two parallel 35 flanges, c c, forming a longitudinal groove or recess extending from its fulcrum B to its outer bent end, as clearly shown in the drawing. Within this groove or recess is placed a spring, A', secured at the inner pivoted end of 40 the lever and reaching to its outer end, where it is bent to conform to the curvature of the bent part C'.

E is a spring, one end of which is fastened in frame A, while its other end bears against the under side of lever C C', tending to throw 45 this in an upward direction.

Upon the needle-bar F is affixed a projecting stud or pin, G, which, on the downward stroke of the bar, strikes lever C C', which is thus kept vibrating up and down at each stroke 50 of the machine.

The flanges c c, at the outer bent end, C', of the lever, are notched, as shown at H, to form a passage for the thread I, which is clamped between lever C C' and its spring A'. In this 55 manner the device acts as an auxiliary tension device, which is operated automatically by the reciprocations of the needle-bar, and serves to keep the thread taut during the formation of the loop, which receives the hook or shuttle (as 60 the case may be) underneath the bed-plate, thus avoiding the slipping of the stitch consequent upon the looseness of the loop on the upstroke of the needle-bar.

We claim as our invention and desire to secure by Letters Patent of the United States— 65

The combination, with the vertically-reciprocating needle-bar of a sewing-machine, of the bent and grooved lever C C', having its fulcrum at B and notched at H, spring A' 70 resting within the grooved lever, and spring E bearing against its under side, the needle-bar being provided with a stud or projection, G, adapted to strike the lever on its down-stroke, substantially as and for the purpose 75 herein shown and described.

In testimony that we claim the foregoing we have hereunto set our hands this 13th day of May, 1880.

AMAND ULYSSE LORINET.

ZACHARIE PRUDENT AUBERTELLE.
